By: *Robert Beardsley* Atty.

UNITED STATES PATENT OFFICE.

ROBERT BEARDSLEY, OF CHICAGO, ILLINOIS.

SHADE HOLDER.

Application filed September 17, 1921. Serial No. 501,375.

To all whom it may concern:

Be it known that I, ROBERT BEARDSLEY, a citizen of the United States, residing at Chicago, in the county of Cook and State of Illinois, have invented certain new and useful Improvements in Shade Holders, of which the following is a description.

My invention relates to improvements in shade holders, and more particularly to a shade holder having quick-acting means adapted to releasably clamp the holder about a lamp socket or other suitable fixture, said clamping or releasing being effected by a single throw of the latching means.

Another object of my invention is to provide a quick-acting shade holder having means associated therewith for varying the internal diameter of the shade holder so as to firmly grip the socket or other fixture to which it is attached and prevent accidental relative movement therebetween.

The invention has among its other objects the production of a device of the kind described which is simple, convenient, compact, durable, reliable, efficient and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts.

Fig. 1 is an elevation of my shade holder as applied to an electric fixture;

Fig. 2 is a plan view thereof;

Fig. 3 is a detail elevation thereof;

Fig. 4 is a perspective of the same;

Fig. 5 is a detail view showing my shade holder as used with a bushing; and

Fig. 6 is a plan view of the shade holder with the bushing.

In the drawings, wherein I have illustrated the preferred embodiment of my invention, 1 indicates any suitable fixture, either electric, gas, candle or the like, to which the shade 2 is to be applied, said shade in the present instance having a series of radial spider arms 3. The shade holder 4 is composed of a band of preferably resilient or flexible material split to form normally

spaced ends 5 and 6. One of the ends, as for instance the end 6, has a pair of ears or lugs 7 formed thereon and preferably integral therewith, said ears having aligned apertures therethrough to pivotally receive a latch or lever 8, the base of said lever having arms 9 extending through said apertures in the ears. The lever 8 also has an elongated slot 10 therethrough, and the end 5 of the band is suitably reduced so as to be slidable in said slot, the tip of the end 5 being suitably enlarged, as shown more clearly in Fig. 4, as at 11, so as to prevent the withdrawal of the end 5 from the slot 10.

It will be seen that as the lever 8 is pivotally thrown back upon the exterior of the band (to the right in Fig. 4), it will pull or draw the end 5 so as to circumferentially overlie the end 6, and thus reduce the diameter of the band to clamp it upon the fixture to which it is applied. The lever 8 is preferably arcuate or curved, as shown in Fig. 6, so as to more nearly conform to the shape of the encircling band and to lie closely thereagainst. Thus it will be seen that the holder may be completely clamped about the lamp socket or other fixture or released therefrom with but a single movement of the latch or lever 8.

A bushing 12, having split ends, may be secured to the inside of the band by any suitable means, as by pins 13, said bushing being of such a thickness, that when the holder is clamped about the fixture, the holder will firmly grip and there will be no relative movement therebetween. If desired, the bushing may be slightly compressible and formed of a plurality of laminae so that any required number of sheets may be removed or added to the bushing to adjust it to the required thickness.

The band is crimped, as shown at 14, at one or more points about its circumference so as to form recesses or channels to receive the arms 3 of the shade, these arms being either removably positioned therein or fixed thereto by soldering, brazing, or by any other suitable and equivalent means. The shade may be attached to the holder in any other suitable way.

Having thus described my invention, it is obvious that various immaterial modifications may be made in the same without departing from the spirit of my invention; hence I do not wish to be understood as limiting myself to the exact form, con-

struction, arrangement and combination of parts herein shown and described, or uses mentioned.

What I claim as new and desire to secure 5 by Letters Patent is:

1. A shade holder comprising a flexible split band adapted to encircle a support, both ends free to move longitudinally and laterally of one another, a lever pivoted on one 10 of the ends of said band and having an elongated slot therethrough, the other end of said band slidably interengaging in said slot, and means at the tip of said last-mentioned end to prevent disengagement 15 from said lever whereby said lever may be pivoted to slidably draw said interengaging end toward it to releasably overlie the end carrying said lever.

2. A shade holder comprising a flexible split band one end of which has a pair of spaced integral ears thereat, a lever pivoted between said ears and having a slot therein, the other end of said band being non-rotatably slidable in said slot and having 20 an integral enlargement at its tip for preventing its withdrawal therethrough, whereby the pivotal clamping movement of 25

said lever will slidably pull said second-mentioned end so as to circumferentially overlie the first-mentioned end.

3. A shade holder comprising a flexible split band, one end of which has a pair of spaced integral ears thereat, a lever pivoted between said ears and having a slot therein, the other end of said band being non-rotatably slidable in said slot and having an enlargement at its tip for preventing its withdrawal therethrough, whereby the pivotal clamping movement of said lever will slidably pull said second-mentioned end so as to circumferentially overlie the first-mentioned end and releasably latch it thereat, and a bushing of laminated material on the interior of said band for minutely adjusting the contracted diameter of said 35 40 45 holder.

In testimony whereof, I have hereunto signed my name in the presence of two subscribing witnesses.

ROBERT BEARDSLEY.
